United States Patent Office

Des. 214,777
Patented July 29, 1969

214,777

CHAIN SAW

John T. Carnahan, Dayton, Ohio, assignor to O & R
Engines, Inc., a corporation of California

Filed Aug. 21, 1968, Ser. No. 13,224

Term of patent 14 years

Int. Cl. D8—02

U.S. Cl. D8—65

FIG. 5.

FIG. 1 is a perspective view of the chain saw of the invention illustrating the top, the rear, and the left side; FIG. 2 is a front elevational view of the saw;

FIG. 3 is a perspective view of the saw illustrating the top, the rear, and the right side;

FIG. 4 is a bottom plan view of the saw; and

FIG. 5 is a perspective view of the saw illustrating the bottom, the front and the left side.

The dominant features of the design are shown in full lines.

What is claimed is:

The ornamental design for a chain saw, as shown and described.
